DETECTOR FOR STOP MOTION MECHANISM
IN WINDING MACHINES

Eugene R. Alderman, South Hadley, Mass., assignor to Foster Machine Company, Westfield, Mass., a corporation of Massachusetts

Application March 25, 1937, Serial No. 133,050

2 Claims. (Cl. 242—37)

This invention relates to winding machines, and has for its object more particularly an improvement in stop motion mechanism for stopping the winding spindle when the yarn on the supply bobbin becomes exhausted and before the exhaust end of yarn has been wound on the package.

In order that the stopping shall occur before the exhaust end of yarn has been run in through the several guiding and tension devices onto the winding package, the improvement provides for a detector mechanism at a point closely adjacent the end of the supply bobbin which will be normally kept inactive by the tension of the yarn coming off the supply bobbin and which will serve to actuate suitable stop mechanism immediately when the last end of the yarn runs off said supply bobbin. By stopping the winding spindle in this manner it becomes feasible to arrange a convenient position for tying in a new end of a full bobbin before the exhaust end runs through the guiding devices and thus avoid the trouble and loss of time of manually threading in the new end.

A further feature of improvement in conjunction with such means for quickly stopping the winding spindle upon exhaust of the supply is an arrangement for having the last end of yarn left hanging in convenient position for the operator to tie in the new supply without the necessity as heretofore of manually rethreading the new end through the several guiding and tension devices and without the trouble of hunting for the exhaust end on the wound package. This arrangement saves the time and labor of the operator and avoids wastage of yarn.

In the following description the term "bobbin" as used is intended to mean any form of supply such as from a bobbin, cop, quill, etc., and the term "yarn" will be referred to as meaning any fiber used in textiles such as wool, cotton, silk, etc., or any material being wound, such as wire, paper, glass, etc.

Full advantages of my new improvement will become more clearly apparent from the following specification, taken in connection with the accompanying drawings, in which

Fig. 1 is a side elevation of a winding machine unit showing the stop motion and its associated mechanism;

Fig. 2 is a similar view in part showing the position of the mechanism when the winding spindle is stopped;

Fig. 3 is a detail view somewhat enlarged showing in front elevation, the latching member;

Fig. 4 is a view along section 4—4 of Fig. 3 looking in the direction of the arrow;

Fig. 5 is a detail view in side elevation of the detector mechanism;

Fig. 6 is a top plan view of the same;

Fig. 7 is a section along line 7—7 of Fig. 5, looking in the direction of the arrows;

Fig. 8 is a view along line 8—8 of Fig. 9, showing in detail a front view of the tripping latch arranged for electrical operation;

Fig. 9 is a side elevation of the detector and tripping mechanisms arranged for operation electrically; and

Fig. 10 is a detached detail view of the supply bobbin spindle and its spring retainer.

The winding machine to which the present invention is applied is of the usual well known character and comprises a main frame 1, swinging support 2 for winding spindle 3, the latter being driven by surface contact of its package 6 with the usual driving roll 4 of the machine. A brake and throw off arm 5 extends beneath and slightly spaced from the yarn package 6 being wound on the spindle 3 and said arm 5 is adjustably mounted upon an angle member 7 pivoted on the main frame at 8. A rocking of said angle member 7 to the dotted line position shown in Fig. 1 will lift the winding spindle 3 and its package 6 from the driving roll 4 and effect stopping of the same by the brake action of said arm 5. The angle member 7 is under the stress of a spring 9 tending at all times to rock it counterclockwise into its stopping position. It is normally held from such rocking action by reason of a forward nose portion 10 integral with the lower arm of the member 7 which is adapted to rest against a cam block 11, the latter forming part of a knock off plate 12 pivoted at 13 on the main frame. The knock off plate 12 carries at its under side a bell crank lever or knock off dog 14 pivoted at 15 thereon and having its downwardly extending arm 16 adapted to fall into position so as to be engaged by teeth of the usual constantly rotating kicker shaft 17. When the said arm 16 is engaged by the kicker shaft 17 the knock off plate is thrown upwardly in the usual manner to release the cam block 11 from beneath the nose 10 of the angle member 7 for stopping the winding spindle, and the parts in this knock off position are shown clearly in Fig. 2.

The knock off dog 14 has extending forwardly thereof a tripping member 18 and is adapted to be held in normal inactive position by a latch 19 as shown in Fig. 1. The latch 19 is in the form of a flat narrow-edged blade fixed to a latch

member 20 pivotally mounted as shown in Fig. 3 by bearings 21 and 22 upon a fixed bearing rod 23 which extends laterally from a bracket 24 extending from the main frame. The latch member 20 has a crank arm 25 which is adjustably connected by a rod 26 to the detecting mechanism hereinafter described. The rocking movement of the latch member 20 upon its bearing rod 23 is limited by a stop piece 27 adapted to be adjustably fastened by a stud screw 28 to said bearing rod 23. The stop piece 27 has spaced bosses 29 and 30, one at each side of the tripping member 20 as shown in Fig. 4. Extending downwardly and forwardly from the main frame 1 is a bracket 31 which supports at its lower forward end a supporting rail 32 extending lengthwise of the machine and upon this rail 32 is affixedly mounted the aforesaid bracket 24 by stud screw 33. It will be understood that winding machines 20 of this character usually comprise several winding units and individual stop mechanisms for the same and that the longitudinally extending rail 32 supports several supply bobbins at intervals along the same. As shown in Fig. 2 a bobbin pin support 34 extends forwardly from the bracket 24 and adjustably supports at its outer end the bobbin pin 35. A base member 36 for seating the bobbin 37 is adjustably fixed in suitable position on said pin 35. As shown in Fig. 10, a spring retainer 38 is mounted on the bobbin pin 35 for firmly retaining the bobbin thereon. This spring retainer is preferably formed of tubular sheet steel with bulbous portions 39 having slits 40 therein so as to compressibly fit within the core of the bobbin and accommodate itself to bobbins having cores of slightly different diameter.

As shown in Fig. 1, yarn *y* is drawn from the supply bobbin upwardly through detecting mechanism and then for a considerable vertical distance to the initial yarn guide and tension device 42, the latter being carried upon arm 41 extending upwardly and forwardly from the main frame of the machine. The initial guide and tension device 42 comprises the usual spring pressed roll members and may have any suitable wire guide, not shown, for keeping the yarn from jumping said roll. From the roll 42 the yarn *y* is led downwardly under and over tension guide rollers 43 and 44 through the eye 45 of the usual drop wire detector and then upwardly again to the traversing guide 46 and thence to the winding package 6 upon the winding spindle 3. The vertical distance between the top of the supply bobbin 37 and the initial yarn guide and tension device 42 is intended to be shown in Fig. 1 as being sufficient to permit a stopping of the yarn by the detector mechanism as hereinafter described, as soon as the last end of yarn leaves the supply bobbin and before it runs over the initial guide device 42. For this purpose the initial guide device 42 is arranged at about the height of the ordinary operator's head whereas the supply bobbin support is about waist high. By this arrangement the exhaust end of yarn will be left hanging from the guide device 42 in convenient position for the operator to tie in the new end of a full bobbin.

The detecting mechanism for determining when the exhaust end of the yarn comes off the supply bobbin and thereupon actuates the stopping mechanism is preferably located as shown in Fig. 1 just above the upper end of said supply bobbin 37. A vertical standard 47 extends upwardly from the longitudinal support rail 32 and

at the upper end of said standard 47 is adjustably mounted a supporting bracket 48. At the forward end of said bracket 48 is mounted a bell crank lever 49-50 pivoted at 51 thereon and the arm 50 of said lever is connected by the 5 previously described connecting rod 26 to the crank 25 of the tripping member 20.

Referring to Fig. 5, a fork finger bracket 52 is fastened to the support bracket 48 and extending from the upper end of said bracket 52 are 10 fixed two parallel horizontal fork fingers of wire 53 and 54. Pivotally mounted on pivot stud 55 of said bracket 52 is a third horizontally extending wire finger 56 located halfway between the aforesaid fixed fingers 53 and 54. The outer ends 15 of the two fixed fingers 53 and 54 are bent in one direction and the outer end of the intermediate finger 56 is bent in the other direction to facilitate the threading of the yarn strand, between said fingers, that is against one side of the two 20 fingers 53 and 54 and against the other side of the finger 56, as will clearly appear in Figs. 5 and 6. A torsional spring 57 is arranged in connection with the movable fingers 56 tending to swing the same between the two fixed fingers 53 25 and 54 in a clockwise direction as shown in dotted lines in Fig. 6. A rear end or tail portion 58 of said movable finger 56 is at the other side of its pivot so as to engage the arm 49 of the bell crank 49-50 previously mentioned, and when 30 said movable finger 56 is permitted to move to its dotted line position as shown in Fig. 6, the bell crank lever 49-50 will be operated in the proper manner for removing the latch 19 from beneath the tripping member 18 and thus cause a stopping 35 of the winding spindle. The inward or clockwise swinging movement of the finger 56 about its pivot 55 is limited to the dotted line position of said finger as shown in Fig. 6, and the outwardly bent end portions of said fingers 40 form a flaring entrance for threading the yarn between the fingers as above stated. The limiting stop for the inward movement of finger 56 is furnished by the lug 29 on stop piece 27 by reason of the connective devices shown.

In the normal running of the winding spindle the yarn as it is drawn off at high speed from the supply bobbin 37 balloons out as shown in Fig. 1 and creates a sufficient tension at each side of the detecting device so that the yarn in 50 traveling between the three fingers of said detecting device will hold the movable finger 56 in substantial parallelism with the two fixed fingers 53 and 54 as shown in full lines in Fig. 6. When the exhaust end of yarn comes off the supply bobbin the tension of the yarn below the detecting device ceases and the movable finger 56 is permitted to swing inwardly to its dotted line position shown in Fig. 6 whereby as described the tail end 58 of said movable finger actuates the 60 bell crank 49-50 which in turn moves the latch 19 from under the trip member 18 and permits the latter to drop. The tripping movement of the knock off dog 18-14 causes the knock off plate to be thrown upwardly by the kicker shaft 17 and releases the tilting angle member 7 which by means of its arm 5 throws up the winding spindle 3 and at the same time applies a brake thereto for stopping it. This stopping will take place before the exhaust end of the yarn reaches 70 the initial yarn guiding tension device 42 whereby the exhaust end will be hanging in convenient position for the operator to tie in a new end of a full supply bobbin which replaces the empty bobbin on the bobbin pin 35. By this arrange- 75

ment the necessity of manually rethreading the end of the new bobbin through the several guiding tension devices is eliminated and the replenishing operation is clearly facilitated.

5 In some cases it is desirable to operate the latch and tripping member electrically and for this purpose the modification shown in Fig. 9 is provided. The main parts of this apparatus are as above described with the exception that 10 the bell crank 49-50 and its connecting rod 26 to the crank rod 25 of the tripping member are eliminated. As shown in Fig. 9 an electro-magnetic device 60 is mounted on the bracket 24 and has its pole pieces 61 arranged in near but 15 normally spaced relation from an armature member 62 which is adjustably carried upon the arm 25' of the trip member 20. The energizing circuit of the electro-magnetic device 60 is from an electrical source of supply, not shown, through 20 wires 63 connected to each side of the electro-magnetic device 60 and to a movable switch member 64 pivoted on an insulated pivot 65 upon the bracket 48. A fixed switch member 66 is mounted on said bracket 48 and has a return wire 67 25 connected back to the electrical source of supply. The movable switch member 64 has a weighted portion 68 at the other side of its pivot to normally hold it in open position with respect to the fixed contact 66. The tail end portion 58 of the 30 movable finger 56 bears against one side of the movable contact 64 to move it into circuit closing position with respect to 66 whenever the finger 56 is moved into its dotted line position as shown in Fig. 6. The fixed switch member 64 furnishes 35 a limiting stop for the inward swinging of the finger 56. When the energizing circuit for the electro-magnetic device 60 is closed as described the armature 62 will be attracted to move the latch 19 from under the tripping member 18 and 40 cause the stopping of the winding spindle in the manner previously described.

I claim:

1. In a winding machine in combination, a winding spindle, a supply bobbin and a support 45 therefor, an initial guide device for yarn located vertically at a sufficient distance above said supply bobbin to permit the yarn running off said supply bobbin being stopped within said distance, whereby the end of a new bobbin supply may be 50 tied to the end of the exhausted bobbin supply in the space between said bobbin support and said initial yarn guide device, and detecting mecha-

nism located above the bobbin on said support, comprising a pair of fixed fingers spaced slightly apart, and a movably mounted finger located between said fixed fingers, said fingers being adapted to receive the running yarn in bearing relation 5 therebetween, viz, over the fixed fingers and under the movable finger, means causing the movable finger to press against the yarn bridging the fixed fingers and to move relatively to said fixed fingers when the yarn is absent or sufficiently slack in tension, a stop motion mechanism comprising means to stop said winding spindle including a tripping member and a latch to hold said tripping member against release, an electromagnetic device for moving said latch in 10 release of said tripping member, an electric circuit and switch for said electric magnetic device, and means operable by said movable finger to actuate said switch.

2. In a winding machine in combination, a 20 winding spindle, a supply bobbin and a support therefor, an initial guide device for yarn located vertically at a sufficient distance above said supply bobbin to permit the yarn running off said supply bobbin being stopped within said distance, 25 whereby the end of a new bobbin supply may be tied to the end of the exhausted bobbin supply in the space between said bobbin support and said initial yarn guide device, and detecting mechanism located above the bobbin on said support and between said bobbin and the initial guide device, said detecting mechanism comprising a grid guide of spaced fixed fingers and an intermediate movable finger adapted to receive the yarn in running relation therebetween, viz, 30 over the fixed fingers and under the movable finger, said movable finger having limited movement inwardly between said fixed fingers, said fingers being so formed at their outer portions that when said movable finger is in the inmost 35 position a flaring entrance is provided for threading the yarn between said fingers in running relation, means causing the movable finger to press against the yarn bridging the fixed fingers and to move relatively to said fixed fingers when 40 the yarn is absent or sufficiently slack in tension, a stop motion mechanism comprising means to stop said winding spindle, and means operable by said movable finger to actuate said stop motion mechanism.

50

EUGENE R. ALDERMAN.
